UNITED STATES PATENT OFFICE.

EMMA T. MILLS, OF CORTLAND, NEW YORK.

DESIGN FOR A BUCKET.

SPECIFICATION forming part of Design No. 28,095, dated December 28, 1897.

Application filed November 10, 1897. Serial No. 658,100. Term of patent 7 years.

To all whom it may concern:

Be it known that I, EMMA T. MILLS, a citizen of the United States, residing at Cortland, in the county of Cortland and State of New York, have invented and produced a new and original Design for a Bucket, of which the following is a specification, reference being had to the accompanying drawing, forming a part thereof.

10 The drawing represents in perspective a bucket showing the design.

The leading or material feature of the design consists in the rounded or curved portion A of the body of the bucket, which tapers inwardly from top to bottom. At the

front the body portion is flattened, as shown at B, this flattened portion being inclined inwardly from the top of the bucket to the bottom. Extending transversely across the inner side of the flattened portion is a series of 20 flutings or corrugations C.

Having thus described my invention, what I claim as new is—

The design for a bucket, substantially as herein shown and described.

EMMA T. MILLS.
